UNITED STATES PATENT OFFICE

2,387,285

CUTTER CHAIN

Charles F. Osgood, Claremont, N. H., assignor to
 Sullivan Machinery Company, a corporation of
 Massachusetts

Application November 1, 1940, Serial No. 363,924

18 Claims. (Cl. 262—33)

This invention relates to kerf-cutting means, and more particularly to improvements in cutter chains especially designed for use in the cutting of kerfs in coal and embodying improved supporting and holding means for the cutter bits.

An object of the present invention is to provide an improved kerf-cutting means. Another object is to provide an improved cutter chain especially designed for use in the cutting of kerfs in coal. A further object is to provide an improved supporting and holding means for the cutter bits of a cutter chain. Yet another object is to provide an improved cutter bit holder. A still further object is to provide an improved cutter bit holder for a cutter bit of the double-ended, reversible type, commonly known as a "throw-away" bit. Still another object is to provide an improved cutter bit holder adapted to use in a chain block of a standard cutter chain. Yet another object is to provide an improved detachable bit holder having a pivoted bit holder part for holding the cutter bit in cutting position in the holder. Still another object is to provide an improved detachable bit holder having a pivoted bit holder part engageable with an exterior surface of a chain block wholly outside of the block socket for holding a cutter bit in cutting position in the holder. Still another object is to provide an improved bit holder comprising a pair of cooperating hinged holder parts. A further object is to provide an improved cutter bit holder which is simple in design and rugged in construction. Other objects and advantages of the invention will, however, hereinafter more fully appear in the course of the ensuing description.

In the accompanying drawing there are shown for purposes of illustration several forms which the invention may assume in practice.

In this drawing:

Fig. 1 is a side elevational view of a cutter chain with which an illustrative embodiment of the invention is associated.

Fig. 2 is a cross sectional view taken on line 2—2 of Fig. 1.

Fig. 3 is a view in central longitudinal section taken on line 3—3 of Fig. 2.

Fig. 4 is a detail sectional view taken substantially on line 4—4 of Fig. 1.

Fig. 5 is a detail sectional view taken substantially on line 5—5 of Fig. 1.

Fig. 6 is a perspective view of the improved bit holder.

Fig. 7 is a sectional view, similar to Fig. 3, showing a modified form of the invention.

Fig. 8 is a sectional view, similar to Fig. 3, 55

showing another modified form of the invention.

Fig. 9 is a sectional view, similar to Fig. 3, showing still another modified form of the invention.

5 In the several embodiments of the invention disclosed herein, the improved cutter bit holder is associated with a standard cutter chain of the type especially designed for use in the cutting of kerfs in coal. The cutter chain consists of a 10 series of chain blocks 1 pivotally connected together by strap links 2, and each chain block has a socket 3 arranged at right angles to the path of travel of the cutter chain. The block socket is preferably generally rectangular in cross section and at its inner end opens into a transverse opening 4. The chain block is threaded at 5 for the reception of a standard set screw 6. The improved bit holder, in the embodiment 15 of the invention shown in Figs. 1 to 6, inclusive, is generally designated 7 and has a head 8 and an integral shank 9, the latter being of rectangular cross section for reception in the chain block socket 3. Extending obliquely through the holder head is a socket 10, herein preferably of 20 polygonal cross section, adapted to receive a cutter bit, generally designated 11, of a conventional design. Secured within the holder head and traversing the bit-receiving socket is a hardened metal cross pin 12, and pivotally mounted on 25 projecting ends of this pin are the side arms 13 of a front holder part 14, herein in the form of a bit clamp, and the sides of the holder head are preferably cut away at 15 to receive the side arms 13, in the manner shown. The ends of the 30 cross pin are preferably headed or peened over to retain the side arms of the hinged front holder part in position thereon.

The cutter bit 11, shown most clearly in Figs. 3 and 4, may be of the same general type as that shown in the patent to Ross 2,020,215, although the bit shape may assume various conventional forms without departing from the spirit of the invention. The cutter bit disclosed herein is of triangular shape in side elevation and of polygonal cross section and has plane cutting faces 16, 16 formed, so to speak, one at each of the equal sides of the triangle; and the cutting faces, at the extremities of the cutter bit, terminate in cutting points 17, 17. The plane cutting faces 16, 16 are of elongated diamond shape and are individually symmetrical as to both major and minor axial lines. This cutter bit is of the so-called "throw-away" type and, when both cutting points become dull, may be discarded due to its extremely inexpensive design.

The cutter bit is insertible in the socket 10 of the holder head with its inner, inactive cutting face resting against the cross pin 12. The cross pin therefore serves two purposes in that it acts both as an abutment for the cutter bit and a pivot for the front holder part 14. The pivoted front holder part 14 has a surface 18 engageable with the inner portion of the active cutting face of the cutter bit and a surface 19 engageable with the exterior surface 20 of the chain block outside 10 of the block socket.

When the holder shank 9 is inserted in the chain block socket 3, the surface 19 of the hinged front holder part 14 engages the exterior block surface 20, so that upon further insertive movement of the holder shank in the block socket, the surface 18 of the front holder part engages the inner portion of the active front cutting face of the cutter bit to hold the latter in cutting position in the holder head socket with its inner, inactive cutting face resting firmly against the cross pin 12. The set screw 6 is then adjusted into engagement with the holder shank for firmly securing the holder in position on the chain block. It is accordingly evident that the hinged front holder part 14 is swingable outwardly into engagement with the front cutting face of the bit to prevent exit of the cutter bit from the holder head socket, and is swingable inwardly out of engagement with the cutter bit to permit forward endwise release of the bit from the holder head socket.

The several modified embodiments of the invention shown in Figs. 7, 8 and 9 are broadly similar to that described above. In these embodiments, however, the set screw opening 21 in the chain block 22 is inclined with respect to the path of travel of the cutter chain to enable the inner end of the set screw to engage an inclined surface 23 on a holder shank 24 so that when the set screw is tightened the holder shank will be forced inwardly within the holder block socket. In Fig. 7 a holder head 25 has a front recess 26 for receiving a cutter bit, generally designated 27. This cutter bit is of trapezoidal shape in side elevation and has cutting points 28, 28 at its opposite ends, these points being formed at the extremities of a front plane cutting face 29. The pivot pin 30 for a front holder part 31, in this instance, does not serve as a bit abutment, and the inner, inactive end of the cutter bit engages an abutment surface 32 on the holder head. The pivot pin 30 is secured within the holder head and is spaced rearwardly from the front bit abutment surface 32 in the manner shown. The hinged front holder part 31, as in the form of the invention above described, serves as a bit clamp and has a surface 33 engageable with the front bit face 29 and a surface 34 engageable with the exterior of the chain block. When the set screw is tightened, the holder shank is forced inwardly within the chain block socket and the pivoted front holder part, due to its engagement with the exterior surface of the chain block, engages the cutter bit to clamp the cutter bit firmly against release from the holder head recess. In Fig. 8 the cutter bit, generally designated 35, is crescent shaped and has a curved rear surface 36 and a plane front cutting face 37, the latter terminating at the opposite extremities of the bit in cutting points 38, 38. The forward cutting face 37 of the bit is notched at 39 midway between the cutting points, and the pivoted front holder part 40, which is pivoted on a cross pin 41 secured within the holder head 42, has a portion

43 receivable in the bit notch to hold the cutter bit against endwise displacement from the holder. The rear curved surface of the cutter bit is seated within a recess 44 at the forward side of the holder head. When the set screw is tightened, the holder shank 42' is forced inwardly within the chain block socket and the pivoted front holder part, due to its engagement with the exterior surface of the chain block, engages the cutter bit with its portion 43 received in the bit notch 39, so that the cutter bit is firmly held in cutting position within its recess 44 in the holder head. In Fig. 9 a bit-receiving socket 45 extends obliquely completely through the holder head 46, so that the rear, inactive cutting end of a cutter bit, generally designated 47, extends rearwardly through the socket into engagement with the exterior surface of the chain block at the rear side of the block socket. The cutter bit, in this instance, is of trapezoidal shape in side elevation and has relatively inclined plane cutting faces 48, 48 lying in the sides of a dihedral angle and terminating in cutting points 49, 49 at the opposite extremities of the cutter bit. The cutter bit has its active cutting point projecting forwardly and outwardly from the holder head socket, and the pivoted front holder part 50, which is hinged at 51 on the holder head, has a surface 52 engageable with the inner portion of the active cutting face of the bit, to prevent forward exit of the bit from the holder socket. The pivoted front clamp part has a surface 53 engageable with the exterior surface of the chain block at the forward side of the block socket. The inner, inactive cutting face of the cutter bit rests firmly against the exterior surface of the chain block, and when the set screw is tightened the holder shank 54 is forced inwardly within the block socket and, due to the engagement of the pivoted front holder part with the exterior surface of the chain block, the surface 52 on the holder part engages the inner portion of the active cutting face of the bit to clamp the cutter bit firmly in cutting position. As in Figs. 45, 7 and 8, the cross pin secured within the holder head serves only as a hinge pin. Also in these three modified embodiments, the set screw when tightened effects automatic clamping of the cutter bit firmly in cutting position with a vise-like action since insertive movement of the holder shank within the block socket automatically effects tightening of the front holder part. Otherwise the embodiments of the invention shown in Figs. 7, 8 and 9 are similar to that shown in Figs. 1 to 6, inclusive.

As a result of this invention, it will be noted that an improved kerf-cutting cutter chain is provided having improved cutter bit supporting and holding means for firmly supporting and holding a cutter bit in cutting position on a chain block. It will further be noted that by the provision of the improved cutter bit holder embodying a hinged front holder part engageable with the exterior of the chain block wholly outside of the block socket, the cutter bit is firmly clamped in cutting position on the block. It will further be noted that in the several embodiments of the invention, the cutter bit holder is of an extremely simple and inexpensive design and may be used in a standard chain block. Other uses and advantages of the invention will be clearly apparent to those skilled in the art.

While there are in this application specifically described several forms which the invention may assume in practice, it will be understood that

these forms of the same are shown for purposes of illustration and that the invention may be embodied in various other forms without departing from its spirit or the scope of the appended claims.

What I claim as new and desire to secure by Letters Patent is:

1. A detachable cutter bit holder adapted for mounting on a chain block of a cutter chain, comprising a head and a shank, the latter adapted for reception in a chain block socket and said head having a bit-receiving socket, and a front holder part hingedly connected at one end to said holder head at the outer end of the holder and engageable at its other end with a cutter bit received in said head socket for holding a cutter bit in cutting position within said head socket.

2. A detachable cutter bit holder comprising a head and a shank, said head having a bit-receiving socket, a front holder part hinged to said holder head and having a surface engageable with a cutter bit received in said socket for holding a cutter bit in cutting position within said socket, and a cross pin fixed within said holder head and traversing said socket, said pin serving as an abutment for the inner end of a cutter bit received in said socket and also as a pivot for said hinged front holder part.

3. A detachable bit holder adapted for mounting on a chain block of a cutter chain, comprising a head and an integral shank, the latter adapted for reception in a socket of a chain block and said head having a socket adapted to receive a cutter bit, and a front holder part hingedly connected to said holder head at the outer end of the holder, the hinge located near the rear side of said holder shank, said hinged front holder part swingable about its hinge into engagement with a cutter bit in said head socket and engageable with a chain block for holding a cutter bit against release from said head socket.

4. A cutter-bit-holding means comprising a member having a socket adapted to receive a cutter bit, a cross pin secured to said member and traversing said socket and against which a cutter bit received in said socket is adapted to rest, and a bit-holding member pivotally mounted on said pin and engageable with a cutter bit in said socket for holding the bit against release from said socket.

5. A cutter bit supporting and holding means comprising a holder member having a socket adapted to receive a cutter bit, a holder part hinged to said holder member and adapted to engage a cutter bit received in said socket for preventing release of the bit from said socket, and an element secured to said holder member and traversing said socket and providing an abutment against which a cutter bit received in said socket is adapted to rest, said abutment-providing-element also providing a pivotal mounting for said hinged holder part.

6. In a cutter chain, the combination with a chain block having a socket, of a detachable bit holder having a shank receivable in said block socket and an integral head disposed outside of said socket, said head having a recess for receiving a cutter bit, and a holder part hinged at one end to said holder head at the outer end of the holder and at its other end engaging the exterior surface of said chain block outside the block socket and at said latter end engageable with a bit in said head recess for preventing release of the bit from said recess.

7. In a cutter chain, the combination with a

chain block having a socket, of a bit holder comprising pivotally connected holder parts cooperating to secure a cutter bit in cutting position on said block and means for pivotally connecting said holder parts at the bit-securing end of the holder, one of said holder parts having a shank received in said block socket and the other holder part engageable at the end thereof remote from its pivot with an exterior surface of said

chain block wholly outside of said block socket when the holder is in bit holding position with respect to the block.

8. In a cutter chain, the combination with a chain block having a socket, of a bit holder comprising pivotally connected holder parts cooperating to hold a cutter bit in cutting position on the chain block, and means at the outer end of the holder for pivotally connecting said parts, one of said parts having a shank receivable in said block socket and the other part disposed wholly outside of said block socket and engageable at the end thereof remote from its pivot with an exterior surface on the chain block when the holder is in bit holding position with respect to the block.

9. In a cutter chain, the combination with a chain block having a socket, of a bit holder for holding a cutter bit in cutting position on the chain block comprising cooperating bit holder parts hinged together, and means at the outer end of the holder for hingedly connecting said parts, one of said parts having a portion receivable in said block socket and the other of said parts being disposed wholly outside of the block socket and engageable at the end thereof remote from its hinge with an exterior surface on the chain block when the holder is in bit holding position with respect to the block.

10. In a cutter chain, the combination with a chain block having a socket, of a bit holder for securing a cutter bit in cutting position on said chain block comprising cooperating bit holder parts hinged together, and means at the outer end of the holder for hingedly connecting said parts, one part having a socket adapted to receive a cutter bit and a portion receivable in said block socket and the other part having at the end thereof remote from its hinge spaced surfaces one engageable with a cutter bit in said bit-receiving socket and the other surface engageable with an exterior surface on said chain block, said latter part being disposed wholly outside of said block socket when the holder is in bit holding position with respect to the block.

11. In a cutter chain, the combination with a chain block having a socket, of a bit holder receivable in the block socket for holding a cutter bit in cutting position on the chain block comprising a pair of cooperating holder parts hinged together, and means at the outer end of the holder for hingedly connecting said parts, one part having a bit-receiving opening extending therethrough, and a cutter bit received in said opening with its rear end resting on an exterior surface of said chain block, and said other part engaging an exterior surface on the chain block wholly outside of the block socket when the holder is in bit holding position, said latter part engaging said cutter bit for holding the latter against endwise release from said opening.

12. In combination, a cutter-bit-holding means comprising cooperating holder parts hinged together at the outer end of the holding means, one part having a recess for receiving a cutter bit, and a cutter bit received in said recess and having a notch, said other holder part having

a portion received in said bit notch for preventing release of said bit from said recess.

13. In a cutter chain, a chain block having a socket, and holder means for securing a cutter bit in cutting position on said block comprising cooperating, relatively swingable holder parts hinged together at the outer end of the holder means, one part having a portion disposed in said block socket and the other part swingable at one end about its hinge and disposed wholly outside of said block socket when the holder means is in bit holding position.

14. In a cutter chain, a chain block having a socket, and holder means for securing a cutter bit in cutting position on said block comprising cooperating holder parts hinged together at the outer end of the holder means, one part having a portion disposed in said block socket and the other part swingable about its hinge and disposed wholly outside of said block socket and engageable at the end thereof remote from its hinge with an exterior surface on the chain block when the holder means is in bit holding position.

15. A detachable bit holder adapted for mounting on a chain block of a cutter chain, comprising a head and a shank, the latter adapted for reception in a socket of a chain block and said head having a bit-receiving recess, a double-pointed reversible cutter bit seated in said head recess with a cutting point projecting outwardly therefrom in position to cut, and a member hingedly connected at one end to said head at the outer end of the holder in adjacency to said bit-receiving recess, said hinged member operable to engage at its other end a portion of the projecting cutting point for preventing displacement of the bit from its recess.

16. A detachable bit holder adapted for mounting on a chain block of a cutter chain, comprising a holder member having a bit seat, a double-pointed reversible cutter bit seated in said holder member with a cutting point projecting forwardly and upwardly in cutting position with said projecting point presenting a flat front face inclining slightly downwardly and rearwardly from

the extremity of the cutting point, and a member hingedly connected to said holder member at the outer end of the holder in adjacency to the bit seat, the hinge axis located on the holder in advance of the rearmost point of contact of the bit with the bit seat and said hinged member swingable upwardly about its hinge upon insertion of the holder shank into a block socket to engage a portion of said front bit face to block exit of the bit from its seat.

17. A detachable bit holder adapted for mounting on a chain block of a cutter chain, comprising a head and a shank, the latter being adapted for reception in the socket of a chain block and adapted for engagement by securing means on the block, said head having a bit-receiving recess, a double-pointed reversible cutter bit seated in said head recess with a cutting point projecting outwardly therefrom in position to cut, and a member hingedly connected to said head at the outer end of the holder in adjacency to said head recess, the hinge located on the holder at a point outside of the point of engagement of the securing means with said shank, said hinged member engaging said bit upon insertive movement of the holder shank in a socket of a chain block.

18. A bit holder adapted for mounting on a chain block of a cutter chain, comprising a head and a shank, the latter being adapted for reception in the socket of a chain block and said head having a bit-receiving socket, a double-pointed reversible cutter bit having one portion disposed in said head socket and the other portion projecting therefrom, and a bit-securing element hinged at one end to said head at the outer end of the holder and having spaced abutment surfaces at its other end, one of said abutment surfaces adapted for engagement with an exterior surface of a chain block and the other abutment surface engageable with the projecting portion of said cutter bit, said hinged element swingable on its hinge into and out of bit-securing engagement with said projecting bit portion.

CHARLES F. OSGOOD.
